[57] CLAIM

The ornamental design for a knee pad for crawling infants, as shown and described.

DESCRIPTION

FIG. 1 is a front elevational view of a knee pad for crawling infants showing my new design;

FIG. 2 is a rear elevational view thereof;

FIG. 3 is a right side view thereof;

FIG. 4 is a left side view thereof;

FIG. 5 is a top plan view thereof; and

FIG. 6 is a bottom plan view thereof; and,

FIG. 7 is a perspective view thereof, the infant shown in broken lines is for illustrative purposes only and forms no part of the claimed design.
